UNITED STATES PATENT OFFICE

GEORGE F. HARTER, OF SPRINGFIELD, MASSACHUSETTS, ASSIGNOR TO THE STANDARD ELECTRIC TIME COMPANY, OF SPRINGFIELD, MASSACHUSETTS, A CORPORATION OF CONNECTICUT

ELECTRIC CLOCK SYSTEM

Application filed May 2, 1929. Serial No. 359,830.

This invention relates to electric clock systems in which impulses are transmitted from a master clock or other control apparatus to secondary clocks having electro-magnets or other means for advancing the hands in response to the impulses, and particularly to systems in which the secondary hands are advanced in direct response to the impulses rather than indirectly through a rewinder which stores energy derived from the impulses for driving the hands continuously.

Objects of the invention are to provide a system in which any one of the secondary 15 clocks, if too fast or too slow, is corrected at predetermined intervals, as for example at the end of each hourly cycle, automatically and without interference with the normal operation of another secondary clock in the 20 system, which requires only a single circuit (two wires or one wire and ground) between the control apparatus and the secondary 25 clocks while permitting the use of a multiple circuit if desired, which is simple and economical in construction and reliable and durable in use, and which is generally superior to prior systems of this character.

The invention is applicable to control apparatus for transmitting impulses of different characteristics (such as high and low voltage impulses or alternating current and direct current impulses or impulses which differ both in magnitude and also in kind of current) and at different time intervals (such as once per hour and once per minute respectively) together with secondary clocks normally driven by one kind of impulses and periodically synchronized by the other kind of impulses. While slow secondaries may be advanced to synchronism in various ways, preferably a series of fast impulses are transmitted thereto during the period between the synchronizing or starting impulse and the next preceding normal or driving impulse, thereby to bring any of the secondaries which may be slow into position to be started in synchronism with all the other secondaries when the starting impulse (of high voltage or alternating current or otherwise different) is transmitted.

By making the periods of time between the starting impulse and the first and last normal driving impulses substantially equal to the periods between succeeding normal impulses, the starting impulses and the driving impulses (other than said fast impulses) together constitute a series of regular impulses transmitted at constant predetermined time intervals throughout recurrent cycles (every minute throughout hourly cycles, e. g.) the starting impulse involving merely a change in the character (magnitude or kind of current) of impulse and constituting an altered driving impulse of the aforesaid regular series.

The secondary clocks are characterized by an electromagnet or other means for advancing the hands in response to the driving impulses (minute impulses in the aforesaid example) until the hands reach predetermined positions (with the minute hands in the 60-minute positions, e. g.) together with means for then rendering the aforesaid means ineffective further to advance the hands until a starting impulse (of different voltage or different kind of current) is received. If a secondary be slow the aforesaid fast impulses also function as driving impulses just before the starting impulse initiates a new cycle or conditions the secondary clocks for a new cycle.

For the purpose of illustrating the genus of the invention typical concrete embodiments are shown in the accompanying drawings in which

Fig. 1 is a diagram of the system;

Fig. 2 is an elevational view of the timer of the master clock;

Fig. 3 is an elevational view of a secondary clock movement differing somewhat from that shown in Fig. 1, and

Fig. 4 is a diagram similar to Fig. 1 showing a modification using direct and alternating current.

The particular embodiment of the invention shown in Fig. 1 comprises a master clock having a circuit closer 1 which closes circuit at regular intervals such as once per minute, another circuit closer 2 which closes circuit at more frequent intervals such as once per

second, a circuit controller 3 normally standing in the neutral position shown in Fig. 1 and closing either circuit 4 or circuit 5 when moved to its lower or upper positions respectively, 5 a timer 6 for controlling the circuit closer 3 and turning at a constant speed, preferably one revolution per hour, an electromagnet 7 for controlling switch 8, the switch normally engaging contact 9 and being 10 lifted into engagement with contact 10 when the magnet 7 is energized, an electromagnet 11 controlled by the switches 1 and 2 for closing the switch 12 when energized, and a transformer having a primary 13 connected 15 to a source of alternating current through switch 12 and a secondary 14 connected to a rectifier 15 through switch 8, the rectifier 15 being connected across the entire secondary when the switch 8 is in upper position and 20 being connected across only a part of the secondary when the switch is in the lower position.

The periphery of the timer 6 engages the switch arm 3 through a lug 16 which is held 25 against the timer by spring 17. The periphery is provided with a cam projection 18 which depresses the switch arm 3 into contact with the terminal of circuit 4 for a brief interval during each revolution of 30 the timer, as for example from fifty-nine minutes and ten seconds to fifty-nine minutes and forty seconds. Immediately following the projection 18 is a depression 19 into which the lug 16 is moved by spring 17 as 35 soon as the projection passes, preferably just before the master clock reaches the sixty-minute position, thereby to close circuit 5 while the minute circuit closer 1 sends the sixtieth minute impulse. The timer 6 is also 40 provided with any number of depressions 20 and 21 to permit the circuit closer 3 to close the circuit 5, through electromagnet 7 and source 22, at intervals intermediate the sixty-minute positions, for example while the circuit closer 1 sends the nineteenth and thirty-ninth minute impulses.

The angular positions of the projection 18 and the depressions 19, 20 and 21 are indicated in Fig. 2 where the numerals at the ends 50 of the radial lines indicate the times when the respective points of the circumference of the timer intersected by the radial lines pass the lug 16 on arm 3.

The secondary clock movement diagrammatically illustrated in Fig. 1 comprises an electromagnet D for driving the ratchet wheel 23 through a pawl 24 on arm 25 pivoted at 26. Arm 25 carries a stop 27 for engagement with a second ratchet wheel 28 fast to 60 shaft 29 upon which the ratchet wheel 23 is fastened to prevent overthrow by pawl 24, a pawl 29' pivoted at 30 and engaging with ratchet wheel 23 preventing retrograde movement of the ratchet wheels. Fast to 65 shaft 29 is an arm 30 for engagement with an

insulating lug on a switch spring 31 normally engaging contact 32 and moved by arm 30 into engagement with contact 33 when the secondary clock reaches a predetermined position (e. g. the sixty-minute position as 70 indicated by the minute hand 34 in Fig. 1). The electromagnet D is connected across the rectifier 15 through switch 31 and contact 32, except when the clock movement is in the position shown in the Fig. 1, at which time 75 the resistance 37 is included in the circuit.

The operation of the system is as follows: With the switch 3 normally standing in neutral position at the master clock the minute circuit closer 1 energizes electromagnet 11 once per minute, thereby closing switch 12 at minute intervals to send minute impulses to the secondary clocks, the switch 8 standing in the lowermost position so that these impulses are of comparatively low voltage (for example six volts). With switch 31 at the secondary clock in upper position these impulses are transmitted to the electromagnet D to advance the secondary hands through a one-minute interval at each impulse. Between the fifty-nine and sixty-minute positions of the master clock the switch 3 is depressed to connect the seconds impulse circuit-closer 2 in circuit with the electromagnet 11, thereby to send impulses once per 95 second to the secondary clocks during a part of this minute, for example from fifty-nine minutes and ten seconds to fifty-nine minutes and forty seconds, thereby rapidly to advance to the sixty-minute position any one 100 or more of the secondary clocks which may be slow.

In this connection it is noted that in this and the following illustrations the secondary clocks are intended to advance from their fifty-nine minute positions to their sixty-minute positions when the master clock reaches its fifty-nine minute position (and likewise at every other minute position) so that the secondary clocks, if running normally, are never behind the master clock; although it will of course be understood that the secondaries might be adjusted to advance to each new position only when the master clock has reached that position.

When the secondary clocks have reached the sixty-minute position, the resistance 37 at each secondary is included in circuit as illustrated at the bottom of Fig. 1, this resistance being sufficient to render the low-voltage 120 impulses ineffective to actuate the electromagnet D. In the case of those secondary clocks which are on time the resistance 37 will be included in circuit on the fifty-ninth impulse of the minute circuit closer 1. In the 125 case of those secondary clocks which are too fast the resistance 37 will be included in circuit before the master clock has depressed the switch 3, so that all succeeding impulses by either the minute switch 1 or the seconds im- 130

5 pulse switch 2 will be ineffective to actuate the electromagnets D until the sixty-minute impulse is transmitted. Those secondary 10 clocks which are too slow will be advanced 5 to the sixty-minute position by the seconds impulse switch 2 as above described.

With the hands of all the secondary clocks in the sixty-minute position, when the timer 6 reaches the sixty-minute position the lug 16 15 on the switch 3 moves into the recess 19, thereby closing the circuit of electromagnet 7 to lift switch 8 into engagement with contact 10 whereupon the entire secondary 14 is connected to the rectifier 15. Thus when the 20 minute hand 1 energizes the electromagnet 11 to close switch 12 at the end of the sixtieth minute, an impulse of higher voltage (for example 12 volts) is transmitted to the secondary 25 clocks, the electromagnets D of which are adjusted to respond to these higher voltage impulses through the resistance 37. Thus the hands of the secondary clocks are started on a new hourly cycle by this high voltage impulse, and after the hands have moved to the one- 30 minute portion the switches 31 are permitted to spring upwardly into engagement with contacts 32, thereby rendering the electromagnets D responsive to the normal impulses of lower voltage. After the high voltage 35 pulse is transmitted by the master clock the lug 16 rides out of the recess 19, thereby restoring the switch 3 to neutral position and permitting the switch 8 to move back against contact 9. The normal low voltage impulses 40 are then transmitted continually for fifty-nine minutes except at the nineteen and thirty-nine minute positions when high voltage impulses are transmitted by providing the additional recesses 20 and 21, so that any secondary 45 clock which failed to respond to the sixty-minute impulse of high voltage (or which failed to receive the impulse due to current interruption or other cause) need not wait a full hour for another starting impulse. 50 Normally the secondary clocks will of course respond to the nineteenth and thirty-ninth minute impulses of high voltage as they do to the low voltage impulses.

Instead of providing the secondary clocks 55 with a single magnet D and switch 31 they may be provided with two magnets D' and S as shown in Figs. 1 and 3, the magnet D' functioning in the same way as magnet D and the magnet S serving to stop the clock movement in the sixty-minute position by providing its armature with a stop 46 in the path of arm 60 47 fast to the shaft 29'. By connecting the two magnets S and D' in series as shown in Fig. 1 and adjusting the winding of magnet S so that it will respond only to high voltage 65 impulses, the clock movements will remain in the sixty-minute position until a high voltage impulse causes electromagnets S to move the stops 46 out of the paths of the arms 47, 70 the same high voltage impulse which ener-

gized magnets S also energizing magnets D' to advance the clock movements one step so that the arms 47 will pass the stops 46 before the latter drop back.

The modification using starting impulses 75 of alternating current shown in Fig. 4 is in large part like the arrangement shown in Fig. 1 and inasmuch as corresponding parts are correspondingly designated they need not be described again. In this modification the switch 12 controlled by relay 11 is placed in the circuit of the secondary 14 instead of the circuit of the primary 13; and the relay 7 controls a double-pole switch 8' instead of a single pole-switch 8. In the lower normal position of the switch 8', with the switch in contact with 9 and 9', the circuit L is connected to the rectifier 15 so that an impulse of direct current is transmitted to the secondary clock each time the switch 12 is closed. The upper contacts 10 and 10' of the switch 8' are connected directly to the secondary 14 so that when the switch 8' is in upper position closure of the switch 12 transmits to line L an impulse of alternating current. The right-hand secondary clock of Fig. 4 is like that shown at the bottom of Fig. 1 except in that a condenser 37' is substituted for the resistance 37. The left-hand secondary 90 shown in Fig. 4 may be constructed as shown in Fig. 3 and connected in a branched circuit with the driving magnet D' in one branch and the resetting or synchronizing magnets S in the other branch in series with a condenser 37'. As in Fig. 1 the secondary clocks 95 become unresponsive to the normal driving impulses when they reach the 59th minute position, moving on to the next position only in response to an impulse of alternating current which passes through the condenser 37'. 100

From the foregoing it will be evident that this invention affords a remarkably simple and reliable clock system. For example the secondary clocks may be fully controlled with a single-circuit magnet or magnets in contradistinction to magnets having a plurality of windings and requiring multiple circuits such as differentially wound magnets heretofore used. Moreover, the secondaries may be synchronized by a momentary starting impulse, 110 preferably lasting only a small fraction of a minute, whereas prior systems have required the application of current for as long as fifteen minutes.

While the impulse of different kind is herein referred to as a starting impulse inasmuch as it initiates a new cycle, it may of course be regarded as the last impulse of each cycle, especially when the secondary clocks are adjusted to move from their fifty-nine-minute 120 positions to their sixty-minute positions in response to the sixty-minute impulse instead of the fifty-nine-minute impulse of the master clock.

Certain features of the illustrated system 125

are claimed in the applications of Saul Keilien, Serial No. 341,176 and Serial No. 341,177, both filed February 19, 1929, and the invention of the present case more particularly concerns the means, such as typified by notches 20 and 21 in controller 6, operative during each cycle of the master clock or other control means for restarting any stopped clock which fails to start at the beginning of a cycle before it has lost so much time that it can not be accelerated to correct time by the rapid impulses transmitted near the end of the cycle.

I claim:

15. 1. An electric clock system comprising secondary clocks of the impulse type, control means operable through a predetermined cycle for intermittently advancing the clocks through corresponding cycles, said control means sending one kind of driving impulses during each cycle and a starting impulse of different kind at the end of each cycle, stop means in each clock for stopping its advance at the end of its cycle if it be too fast, said stop means being responsive to said starting impulse to restart the clock when the control means reaches the end of its cycle, the control means then advancing the clock with driving impulses during the major portion of the cycle, and a controller for sending a starting impulse not only at the end of each cycle but also after a series of intermediate driving impulses so that any stopped clock which fails to respond to the first starting impulse will receive another such impulse before it has lost time corresponding to a full cycle.
20. 2. An electric clock system comprising means for continually transmitting regular impulses at constant predetermined intervals throughout recurrent cycles, means for changing the character of one of said impulses at the same interval of each cycle, and means for producing fast impulses during a short period preceding said latter impulse, said second means also changing the character of another impulse during each cycle after a series of regular impulses.
25. 3. An electric clock system comprising line connections, control apparatus for transmitting over said line connections cycles of regular impulses at constant predetermined intervals, certain impulses of each cycle differing from the others and alternating therewith a plurality of times during each cycle, and fast impulses preceding only one of the different impulses of each cycle, and secondary clocks each comprising hand advancing means responsive to the regular and fast impulses until the hands reach predetermined positions and then responsive only to said different impulse.
30. 4. An electric clock system comprising a control station having circuit connections with secondary clocks, transmitting means

at the control station for sending driving impulses to the secondary clocks during each cycle of the secondary hands and a starting impulse at the beginning of each cycle and again after a series of driving impulses of the same cycle, and means at the secondary clocks for advancing the hands in response to the driving impulses until the hands reach the end of a cycle and then starting a new cycle in response to a starting impulse.

Signed by me at Springfield, Massachusetts, this 30th day of April, 1929.
